UNITED STATES PATENT OFFICE

108,165

DESIGN FOR A FILE

Roscoe Stephens, Folsom City, Calif.

Application September 8, 1937, Serial No. 71,507

Term of patent 7 years

To all whom it may concern:

Be it known that I, Roscoe Stephens, a citizen of the United States, residing at Folsom City, in the county of Sacramento and State of California, have invented a new, original, and ornamental Design for a File, of which the following is a specification, reference being had to the accompanying drawing, forming part thereof,

I claim:

The ornamental design for a file as shown.

ROSCOE STEPHENS.
